UNITED STATES PATENT OFFICE

101,278

DESIGN FOR A STORE FRONT

Abe Johnson, New Haven, Conn., assignor to Johnson Wholesale Perfume Co., Inc., Hamden, Conn., a corporation of Connecticut

Application July 14, 1936, Serial No. 63,839

Term of patent 14 years

To all whom it may concern:

Be it known that I, Abe Johnson, a citizen of the United States, residing in New Haven, in the county of New Haven and State of Connecticut, have invented a new, original, and ornamental Design for Store Fronts, of which the following is a specification when taken in connection with the accompanying drawing:

Fig. 1 is a front elevational view of a store front embodying my design;

Fig. 2 is a sectional view on line 2—2 of Fig. 1; and

Fig. 3 is a partial sectional view on line 3—3 of Fig. 1 looking in the direction of the arrows.

The drawing is shaded to indicate contrasting appearance.

I claim:

The ornamental design for a store front, substantially as shown and described.

ABE JOHNSON.
